UNITED STATES PATENT OFFICE.

FLORA E. JOUSSET AND ALBERT D. JOUSSET, OF NEW YORK, N. Y.

INHALER.

No. 831,004.

Specification of Letters Patent.

Patented Sept. 11, 1906.

Application filed April 4, 1906. Serial No. 309,771.

To all whom it may concern:

Be it known that we, FLORA E. JOUSSET and ALBERT D. JOUSSET, citizens of the United States, residing at New York city, in the county of New York and State of New York, have invented new and useful Improvements in Inhalers, of which the following is a specification.

Our invention relates to inhalers, and more particularly to that class which is adapted to contain some substance to be soaked in some medicinal liquid or preparation, the inhaler then to be inserted in the nostrils of the user, so that all air drawn through same will take up a certain amount of the preparation, thereby proving beneficial to certain diseases of the nasal organs or the throat. These and other objects of the invention will be more fully described in the following specification and set forth in the appended claims.

In the drawings forming a part of this specification and accompanying same like reference characters are used to designate like parts in the various figures.

Figure 1 is a side elevation of our improved device. Fig. 2 is a plan view. Fig. 3 is a side elevation, partly in section. Fig. 4 is a bottom view of same, and Fig. 5 is a side view of the device at right angles to Fig. 1.

The device consists of two perforated bulbs 6 and 7, made up of two sections and joined to each other by a yoke 8 of U-shaped or similar design. At the point where these two sections of the bulbs are joined we may use an ordinary slip-joint where friction is depended upon alone, or they may be threaded to screw together. These bulbs contain within them a similar but smaller bulb 9, also made of two sections and adapted to be held together by the means above described. In Fig. 3 it will be seen that we inclose within this smaller bulb a little raw cotton, silk, or similar substance, which may be impregnated

with some remedy for nasal diseases, or this bulb may contain powders or similar compounds to be inhaled to give the user relief. We adopt the two bulbs in order that the substance contained within may not be inhaled or wasted too rapidly and used away or perhaps prove too irritating to the party using it. These bulbs are constructed with a sufficient space between them in order to fit the nostrils of the average adult; but the yoke 8 is made of metal or similar substance which can be readily bent, so as to adjust the bulbs to the nose of any special size or formation. It is obvious that minor modifications of construction may be resorted to without departing from the essential features of the invention.

Having thus described our invention, we claim—

1. In an inhaler, the combination with perforated bulbs joined by a flexible yoke and made up of two sections each, of smaller perforated bulbs adapted to be contained in the united bulbs.

2. In a nasal inhaler, the combination with perforated bulbs adapted to be adjusted so as to fit within the nostrils, of smaller perforated bulbs adapted to contain medicines and carried within the adjustable bulbs.

3. In a nasal inhaler, the combination with perforated bulbs connected by a yoke and made up of two sections adapted to be fitted together, of a second set of perforated bulbs adapted to be carried within the first and also made up of two sections fitted together.

In testimony whereof we affix our signatures in presence of two witnesses.

FLORA E. JOUSSET.
ALBERT D. JOUSSET.
